UNITED STATES PATENT OFFICE

153,334

DESIGN FOR A LAWN SPRINKLER

Charles Beaver, Philadelphia, Pa.

Application July 26, 1947, Serial No. 140,553

Term of patent 3½ years

(Cl. D91—1)

To all whom it may concern:

Be it known that I, Charles Beaver, a citizen of the United States residing at Philadelphia, in the county of Philadelphia and Commonwealth of Pennsylvania, have invented a new, original, and ornamental Design for Lawn Sprinkler, of which the following is a specification, reference being had to the accompanying drawing, forming a part thereof.

Figure 1 is a perspective view of a lawn sprinkler, showing my new design;

Figure 2 is a top plan view of the head portion of one of the upstanding elements of said design; and

Figure 3 is a fragmentary perspective view, partly in section and with parts broken away, showing one of the elements about the stem portion of said design.

I claim:

The ornamental design for a lawn sprinkler, as shown.

CHARLES BEAVER.
